UNITED STATES PATENT OFFICE.

FRANCIS JONATHAN CLEMENGER, OF NEW YORK, N. Y.

COMBINED RECEPTACLE AND BUFFER.

Application filed March 9, 1926. Serial No. 93,483.

This invention relates to buffers, and more particularly to a combined buffer and receptacle for finger nail polish.

The custom of polishing finger nails is common and buffers for that purpose are widely sold. Such buffers consist usually of a body having a buffing surface of chamois or the like. The polish, usually in the form of powder, is kept in a separate receptacle. The buffer and separate receptacle do not lend themselves readily to the ultimate purpose. One or the other may be misplaced and in any event two separate articles must be handled to complete the operation. It has been suggested heretofore to provide a combined buffer and receptacle, the bottom of the receptacle being perforated to permit the polishing powder to pass through the buffing material overlying the bottom surface. This device does not operate satisfactorily because the buffing material is quickly clogged with the polishing powder which then cannot be sifted from the receptacle. It is the object of the present invention to provide a simple and effective device adapted to act as a receptacle for the polish and to permit the latter to be applied as desired, the receptacle being also provided with a buffing surface to facilitate the polishing operation.

In carrying out the invention the receptacle may be made of any of the metals or of various other materials adapted for such use. It may be of any desired shape. Preferably it comprises an elongated body consisting of upper and lower parts connected by a tightly fitting slip joint and forming a chamber for the polish. The upper part may have a dome forming a convenient handle. It may be provided with perforations through which the polish may be sifted. Such perforations may be closed normally by a suitable solid cover.

The buffing material, which may be of chamois skin, goat skin or closely woven cloth, is secured to the bottom of the lower part of the receptacle in any suitable manner as by the application of an adhesive such as glue thereto or it may be held by a slip ring of metal adapted to engage and hold the edges of the material. A cover of metal or other material may be provided to slip over the buffing surface and thus to protect it from soiling. The cover may be held in

place by a friction fit or suitable spring clips may be provided at the ends thereof.

The device as described affords a useful and convenient receptacle for the polish and it facilitates the application and use thereof by providing a buffering surface which, being attached to the receptacle, is ready for instant use. The polishing material and buffering surface cannot be separately misplaced. The perforations in the upper part of the receptacle permit sifting of the polish. These perforations are not easily clogged and the device cannot thus become inoperative.

The invention will be further described with reference to the accompanying drawing, in which

Fig. 1 is a longitudinal section through the device;

Fig. 2 is a plan view thereof; and

Fig. 3 is a view in perspective showing the cover for the buffering surface removed.

Referring to the drawing, 5 and 6 indicate the upper and lower segments of the receptacle which are connected by a tightly fitting slip joint 7 forming a chamber 8 for the polish. A dome 10 on the upper segment 5 provides a handle for the device. A plurality of openings 11 in the top of the dome permit sifting of the polish from the receptacle. The openings may be closed by a cover 12.

The buffering material 13 covers the bottom of the lower segment 6 and is held in place by a slip ring 14. The buffering material may be secured by an adhesive substance such as glue to the bottom of the lower segment if desired.

A cover 15 for the buffering material 13 may be provided. It may fit snugly about the buffering material so that it will remain in position to afford protection therefor. It may be held in place securely by a spring clip 16 at the ends of the receptacle.

When the device is to be used the cover 15 is removed and the cover 12 is rotated to clear the openings 11. The polish is then sifted on the nails and the buffering material is applied thereto until the desired polish is secured. When the operation is complete the cover 12 may be returned to closed position to prevent escape of the polish and the cover 15 may be replaced.

Various changes may be made in the form and arrangement of the parts as well as in

the nature of the materials of which the device is constructed without departing from the invention or sacrificing any of its advantages.

5. I claim:—

1. A combined receptacle and buffer adapted to facilitate the application of polish to finger-nails comprising a body forming the receptacle and carrying the buffing material, the body port on having perforations above the buffing material through which the polish can be sifted and a cover for the perforations.

10. 2. A combined receptacle and buffer adapted to facilitate the application of polish to finger-nails comprising a body forming the receptacle and carrying the buffing material, a separable cover for the buffing material, the body portion having perforations above the buffing material through which the polish can be sifted and a cover for the perforations.

15. 3. A combined receptacle and buffer adapted to facilitate the application of polish to finger-nails comprising a body formed of upper and lower segments connected by a closely fitting joint, buffing material on the bottom of the lower segment, the upper segment having perforations through which the polish can be sifted and a cover for the perforations.

20. 4. A combined receptacle and buffer adapted to facilitate the application of polish to finger-nails comprising a body formed of upper and lower segments connected by a closely fitting joint, buffing material on the bottom of the lower segment, a separable cover for the buffing material, the upper segment having perforations through which the polish can be sifted and a cover for the perforations.

25. 5. A combined receptacle and buffer adapted to facilitate the application of polish to finger-nails comprising a body formed of upper and lower segments connected by a closely fitting joint, buffing material on the bottom of the lower segment, a dome on the upper segment forming a handle and having perforations through which the polish can be sifted and a cover for the perforations.

30. to finger-nails comprising a body formed of upper and lower segments connected by a closely fitting joint, buffing material on the bottom of the lower segment, a slip-ring 45 securing the buffing material in place, the upper segment having perforations through which the polish can be sifted and a cover 50 for the perforations.

35. 6. A combined receptacle and buffer adapted to facilitate the application of polish to finger-nails comprising a body formed of upper and lower segments connected by a closely fitting joint, buffing material on the bottom of the lower segment, a slip-ring 55 securing the buffing material in place, a separable cover for the buffing material, the upper segment having perforations through 60 which the polish can be sifted and a cover for the perforations.

40. 7. A combined receptacle and buffer adapted to facilitate the application of polish to finger-nails comprising a body formed of upper and lower segments connected by a closely fitting joint, buffing material on the bottom of the lower segment, a dome on the upper segment forming a handle and having 65 perforations through which the polish can be sifted and a cover for the perforations.

45. 8. A combined receptacle and buffer adapted to facilitate the application of polish to finger-nails comprising a body formed of upper and lower segments connected by a closely fitting joint, buffing material on the bottom of the lower segment, a separable cover for the buffing material, a dome on the upper segment forming a handle and having 70 perforations through which the polish can be sifted and a cover for the perforations.

50. Signed at New York city, in the county of New York, State of New York, on this the 6th day of March, in the year 1926 A. D.

FRANCIS JONATHAN CLEMENGER.
